COMBINATION JAR AND BOTTLE OPENER

Bertrand E. Stolpe, Des Moines, Iowa

Application May 13, 1949, Serial No. 2,627

Term of patent 14 years

(Cl. D44—29)

To all whom it may concern:

Be it known that I, Bertrand E. Stolpe, a citizen of the United States and resident of Des Moines, Iowa, in the county of Polk and State of Iowa, have invented a new, original, and ornamental Design for a Combination Jar and Bottle Opener, of which the following is a specification, reference being had to the accompanying drawing forming part hereof, in which:

Fig. 1 is a front view of a combination jar and bottle opener showing my new design;

Fig. 2 is a side elevational view looking toward the left in Fig. 1;

Fig. 3 is a plan view; and

Fig. 4 is a sectional view taken along the line 4—4 in Fig. 1.

I claim:

The ornamental design for a combination jar and bottle opener, substantially as shown.

BERTRAND E. STOLPE.
